ELBERT E. WHITTENBURG, OF INDIANAPOLIS, INDIANA, ASSIGNOR TO THE STANDARD
DEY KILN COMPANY, OF INDIANAPOLIS, INDIANA, A CORPORATION.

JOURNAL-BOX FOR TRUCKS.

1,141,029.

Specification of Letters Patent.

Patented May 25, 1915.

Application filed November 30, 1914. Serial No. 874,743.

To all whom it may concern:

Be it known that I, ELBERT E. WHITTENBURG, a citizen of the United States, and a resident of Indianapolis, county of Marion, 5 and State of Indiana, have invented a certain new and useful Journal-Box for Trucks; and I do hereby declare that the following is a full, clear, and exact description thereof, reference being had to the accompanying drawings, in which like letters 10 refer to like parts.

The object of this invention is to improve the construction of brick cars and the like.

15 The invention has been made particularly in connection with cars for brick drying purposes, but it is not limited to such use. The tracks on which such cars operate are usually in imperfect alinement and, therefore, there is a slight variation in the elevation 20 of the track rails.

The purpose of this invention is to provide a very simple and effective construction which will enable the car to operate satisfactorily on an uneven track; and also to make such construction capable of supporting a very heavy load as is required in handling of clay products.

25 The chief feature of the invention consists in securing to the frame of the car a downwardly extending housing having a convex upper surface and mounting on the ends of the axles journal boxes adapted to loosely fit in said housing and having concave upper bearing surfaces to engage said concave surfaces in the housing. The lower 30 part of the housing surrounds only the outer end of the journal box sufficiently to prevent the escape of the axle and journal 35 boxes. With this arrangement there is quite an extensive bearing surface between the journal box and the bracket, sufficient for any load which the truck could carry. At the same time it is arranged so that the journal 40 boxes can oscillate or otherwise adjust themselves to vertical irregularities in the track.

The full nature of the invention will be understood from the accompanying drawings and the following description and claims:

45 In the drawings, Figure 1 is a vertical transverse section through a truck, showing one wheel and section running in elevation.

tion. Fig. 2 is a section on the line 2-2 of Fig. 1.

The frame 10 is rigid and to its sides the housings 11 are secured. These housings receive the journal boxes 12 mounted by roller bearings on the ends of the axles 13 carried by the wheels 14. Each journal box 12 has flat vertical sides and a transversely curved lower surface and an upper bearing surface 112 which is convex both transversely and longitudinally of the axle. The transverse curvature is shown in Fig. 2, and the longitudinal curvature is shown in Fig. 1, and said longitudinal curvature extends throughout the upper and outer peripheral surfaces of said journal boxes so that said surfaces are substantially concentric with the center of the portion of the axle mounted on the journal box. The inner or bearing surface of the housing 11 has vertical sides, as shown in Fig. 2, and an upper and inner bearing surface concave and curved to receive snugly the journal box.

The foregoing construction is such that the journal box can have but slight transverse oscillatory movement, and may have vertical play, although that is limited because the weight of the car and load will hold the bracket snugly down upon the journal box. The journal box however can oscillate in a plane parallel with the axle to a sufficient extent to enable it to accommodate its structure to the vertical irregularities in the track on which the car operates. And to the foregoing result there is added an extremely large bearing surface between the housing and the journal box so that the journal box will support any load which the car can support and regardless of the vertical irregularities of the track. There is an opening 20 in the bottom of each journal box to let the dirt escape and the lower part of each housing is cut away at 21 to let the dirt escape. Also end opening 22 in the housing and 23 in the journal box are provided so as to register with each other and permit the dirt to escape and an overhanging flange 25 protects the opening 22.

One result of the foregoing structure is that the curvature of the upper parts of the housing and journal box sheds dirt and dust and prevents the same from entering the roller bearings in the journal box and renders it unnecessary to have shields.

The invention claimed is:

1. In a car, the combination with a main frame, an axle, and car wheels carried by the axle, of a housing secured to said frame and having a journal box on the axle and fitting in said housing, the upper surface of said journal box bearing against the inner upper surface of said housing, said engaging bearing surfaces being formed so that the journal box can oscillate in a plane parallel with the axle.
2. In a car, the combination with a main frame, an axle, and car wheels carried by the axle, of a supporting bracket secured to the frame and having a housing thereon with a bearing surface curved longitudinally of the axle and a journal box fitting in said housing having a similarly curved bearing surface for engaging the bearing surface of the housing.
3. In a car, the combination with a main frame, an axle, and car wheels carried by the axle, of a housing secured to said frame which has vertical sides with an upper bearing surface curved longitudinally of the axle, and a journal box upon the axle and fitting in said housing and having vertical sides and an upper convex bearing surface curved so as to conform with the bearing surface of the housing.
4. In a car, the combination with a main frame, an axle, and car wheels carried by the axle, of a housing secured to said frame which has vertical sides with an upper and inner bearing surface curved longitudinally of the axle, and a journal box upon the axle and fitting in said housing and having vertical sides and an upper and convex bearing surface curved so as to conform with the bearing surface of the housing, the curvature of said bearing surfaces being substantially concentric with the portion of the axle in the journal box.
5. In a car, the combination with a main frame, an axle, and car wheels carried by the axle, of a housing secured to said frame which has vertical sides with an upper and inner bearing surface curved longitudinally of the axle, and a journal box upon the axle and fitting in said housing and having vertical sides and an upper convex bearing surface curved so as to conform with the bearing surface of the housing, the lower part of the journal box being partially cut away to permit the escape of dirt.
6. In a car, the combination with a main frame, an axle, and car wheels carried by the axle, of a housing secured to said frame which has vertical sides with an upper and inner bearing surface curved longitudinally of the axle, and a journal box upon the axle and fitting in said housing and having vertical sides and an upper convex bearing surface curved so as to conform with the bearing surface of the housing, the inner and lower sides of said housing being obliquely cut away to a point under the outer portion of the journal box.
7. In a car, the combination with a main frame, an axle, and car wheels carried by the axle, of a housing secured to said frame which has vertical sides with an upper and inner bearing surface curved longitudinally of the axle, and a journal box upon the axle and fitting in said housing and having vertical sides and an upper convex bearing surface curved so as to conform with the bearing surface of the housing, the bottom portions of the housing and journal box being partially cut away to permit the escape of dirt.
8. In a car, the combination with a main frame, an axle, and car wheels carried by the axle, of a housing secured to said frame which has vertical sides with an upper and inner bearing surface curved longitudinally of the axle, a journal box upon the axle and fitting in said housing and having vertical sides and an upper convex bearing surface curved so as to conform with the bearing surface of the housing, and registering openings in the ends of said journal box and bearing bracket.
9. In a truck, the combination with a main frame, an axle, and car wheels carried by the axle, of a housing secured to said frame which has vertical sides with an upper and inner bearing surface curved longitudinally of the axle, and a journal box upon the axle and fitting in said housing and having vertical sides and an upper convex bearing surface curved so as to conform with the bearing surface of the housing, the upper inner edges of the housing and journal box being normally flush with each other.

In witness whereof, I have hereunto affixed my signature in the presence of the witnesses herein named.

ELBERT E. WHITTENBURG.
